COOLING OF PHOTO-COPYING MACHINES

Edward Woodham, Colchester, England, assignor to E. N. Mason & Sons Limited, Colchester, England, a British company

Application July 23, 1954, Serial No. 445,428

Claims priority, application Great Britain
August 5, 1953

3 Claims. (Cl. 95—73)

This invention relates to photo-copying machines of the type wherein a tubular light source or sources is or are located inside a stationary or rotating transparent cylinder or part of a cylinder around which a drawing or other original to be copied and sensitised paper or other material, is moved. As lamps of considerable power are used, a large amount of heat is generated, a considerable proportion thereof being in the infra-red region of the spectrum, thus causing the transparent cylinder to become excessively hot, to the detriment of the drawing or other original and the sensitised material.

As is well known, various systems of ventilation are employed, some of these systems drawing air from the centre of the cylinder by means of metal ducting and thus causing cooler air to flow in at both ends of the cylinder. Air can also be blown in at one end of the cylinder and allowed to pass out at the other end of the cylinder. Air may also be drawn out at each end whilst cooler air is allowed to flow in to the centre through ducting. It is also known to surround the tubular light source by a glass tube capable of transmitting ultra violet light necessary for exposing most types of photo-printing materials. Although the glass tube has been fitted to prevent the transmission of the shorter wave length ultra violet light, which causes the formation of ozone in the surrounding atmosphere, it has also been found beneficial as it absorbs some of the heat given out by the light source and thus prevents the cylinder from becoming too hot.

According to the present invention a photo-copying machine of the type referred to is provided with a transparent jacket of glass or other transparent material, the material sold under the registered trademark "Pyrex," or other heat resisting glass, the jacket being provided with two spaced sets of continuous slots or series of holes or spaced slots along a portion or the entire length thereof, the jacket being located between the tubular light source and the cylinder.

The invention will now be described by way of example with reference to the accompanying drawings, wherein:

Fig. 1 is a cross-sectional view on the line I—I of Fig. 2 on an enlarged scale.

Fig. 2 is a perspective view of a portion of a photo-copying machine.

Fig. 3 is a cross sectional view taken on the line I—I of Fig. 1.

Referring first to Figs. 1 and 2, a transparent jacket of heat resisting glass, consists of two semi-cylindrical parts 2, 2', axially spaced apart by two substantially oppositely located strips 4, provided with slots or holes 14, 14'. These slots or holes, 14, 14' are not necessarily parallel and are preferably wider at the middle portion of the cylinder. The jacket 2, 2' is located between a light source located in a tube 3 and a stationary or rotary transparent cylinder 1 around which latter the drawing or the like to be copied and sensitised material is placed or moved. The ventilating system is so arranged in the cylinder 1 that air is drawn out from each end of the jacket 2, 2' in the di-

rection of the arrows 16, 16' by suction. Cool air thus flows in through the slots or holes 14, 14' after flowing into the opposite ends of the main cylinder as indicated by the arrows 17, 17'.

5 The ventilating system may also be arranged so that the cool air is forced into the ends of the jacket 2, 2' and flows out through the holes or slots 14 and out between the jacket 2 or 2' and outer cylinder 1. The purpose of using a jacket of the material described is that it transmits a large proportion of the longer wavelength ultra-violet light rays whilst absorbing a large proportion of infra-red light rays.

10 By the arrangement according to the invention a transparent ventilating duct is provided which has a selective transparency, whilst allowing beneficial ultraviolet light to reach the sensitised material and at the same time shielding the outer cylinder 1 and the materials around the cylinder 1 from the harmful heating effects of infrared radiations. The light source 3 may in addition be surrounded in the known manner by a glass tube for shielding the light source from direct currents of air from the slots or holes 14 in the jacket. The two halves of the jacket, when formed by two semi-cylindrical parts 2, 2', may be off-set slightly by strips 4 and 4' in relation to each other, as shown in Figs. 1 and 3, so as to cause the air to enter the interior of the jacket tangentially thus providing further means for shielding the light source from a direct current of cooler air.

15 As shown in Fig. 3 three light sources 12, 12', 12'' may be provided.

20 Amongst the advantages of the present invention may be mentioned:

25 1. Delicate original drawings and sensitised material or the like are protected from excessive heat during photo-copying.

30 2. The light source may be operated at its correct temperature, thus giving a higher efficiency.

35 3. Materials with better optical but poorer heat resisting properties than glass, may be employed for the construction of the outer cylinder.

40 I claim:

45 1. In a photo-copying machine having a cylinder and a tubular light source located centrally and longitudinally within the cylinder, the combination comprising, a jacket including a pair of transparent substantially semicylindrical elements located around said light source, means at each side of the elements for connecting and axially displacing the same so that one element is offset laterally from the other, said means having openings for causing air to travel tangentially relative to the inner wall of each

50 element, and forced air means at the ends of said elements for moving air therethrough and between the outer surfaces of said elements and the inner wall of the cylinder.

55 2. In a photo-copying machine having a cylinder and a tubular light source located centrally and longitudinally within said cylinder, the combination comprising a jacket including a pair of transparent substantially semi-cylindrical elements located around said light source, the adjacent ends of said elements being relatively displaced axially, and strips having medial air openings, said strip

60 arranged diametrically relatively to and connecting said substantially semi-cylindrical elements in axially offset relation.

65 3. In a photo-copying machine according to claim 1, the provision of air chambers at opposite ends of said semi-cylindrical elements.
